J. L. BALDWIN,
OVERHEAD CARRIER SYSTEM,
APPLICATION FILED JAN. 24, 1922.

1,425,740.

Patented Aug. 15, 1922.

UNITED STATES PATENT OFFICE.

JAMES L. BALDWIN, OF CHICAGO, ILLINOIS.

OVERHEAD CARRIER SYSTEM.

1,425,740.

Specification of Letters Patent. Patented Aug. 15, 1922.

Application filed January 24, 1922. Serial No. 531,471.

To all whom it may concern:

Be it known that I, JAMES L. BALDWIN, a citizen of the United States, residing at Chicago, in the county of Cook and State of Illinois, have invented new and useful Improvements in Overhead Carrier Systems, of which the following is a specification.

This invention relates to apparatus employed in stores and other mercantile establishments for the transportation of money or parcels, the same consisting of an elevated track upon which carriers travel from various sending terminals or stations to a receiving station, such as the cashier's department, the bundle wrapping department, etc.

The invention relates more particularly to a carrier system in which long distances and frequent curves are encountered, and it is the object of the invention to provide a novel and improved mechanism for moving the carrier through such courses from one floor to another above where the cashier's department or other terminal or receiving station may be located, or to allow it to continue along another horizontal or vertical track on such upper floor.

Another object of the invention is to provide power propulsion for the carrier during its entire trip from the sending station below to the receiving station above; and so on the return trip, if descent by gravity is impracticable.

A further object of the invention is to lend dispatch to the ascent of the carrier by providing an electrical power element, actuated by the mere pressing of a push button.

A still further object of the invention is to provide a mechanism whereby power is used only while the carrier is in action, being even dispensed with for the return or descent where gravity may be resorted to.

Another object of the invention is to design the same devoid of complicated parts, making the structure easy to install and operate, and economical to maintain and use.

In order that the invention may be better understood, reference is had to the accompanying drawing, in which—

Figure 1 is an elevation of the apparatus, partly broken away at an intermediate point;

Fig. 2, is an enlarged elevation of the mechanism at the sending station;

Fig. 3 is a side elevation of such mechanism;

Fig. 4 is an enlarged elevation of the

mechanism at the receiving station, partly in section;

Fig. 5 is a side elevation thereof from the left hand side of Fig. 4; and

Fig. 6 is a cross section on the line 6—6 of Fig. 1.

Referring specifically to the drawing, 10 denotes a typical wire track as used in cash or parcel carrying systems for the guidance of a carrier such as is shown at 11, the track 65 having suitable supports 12, and guards 13. In the present instance, the lower end of the track wire is secured to a table or stand 14 at the sending station. The carrier 11 has an arm 15 for connection with a belt 16 70 whose runs extend in parallel relation from the sending station to the end of the line, following the course of the track wire 10 alongside of the same. The belt has a drive pulley 17 associated with the sending station, and a return pulley 18 at the receiving station, or end of the line. Intermediate these points, twin sets of guide pulleys 19 are distributed, each set being mounted on a pin 20 supported by a guard bracket 21. It 75 will be understood that the provision of the dual guide pulley arrangement is due to the fact that the belt runs move in opposite directions.

In order that the belt may be operated to 85 draw the carrier along its course, an electric motor 22 is secured under the stand 14. From the shaft pulley 23 of the motor, a reduction belt connection 24 is made to a large pulley 25 supported in a stand 26 below. This pulley, as well as the drive pulley 17 previously 90 mentioned are free on a shaft 27, but are designed to become operatively connected through an automatic clutch. As shown more clearly in Fig. 2, the pulleys 25 and 17 95 carry clutch teeth 25^a and 17^a between them, the teeth 25^a being pivoted in ears 25^b on the face of pulley 25, and having extensions in the form of ball stems 25^c. A coil spring 25^d is interposed between each ball stem and 100 the face of the pulley to force the stem out, thereby holding its tooth 25^a in retracted position, and out of the path of the teeth 17^a. However, when the pulley 25 is in motion, the ball stems 25^c recede by centrifugal 105 force, whereby the teeth 25^a advance into the path of the teeth 17^a, and lend motion to the pulley 17. The object of providing a clutch rather than a direct connection between the pulleys 25 and 17 is to operatively connect 110

the pulleys only when the motor is in action; or, in effect, to cut the motor out of the belt line when its power is not required, for a purpose to be later made evident.

5 The top of the stand is of course drilled to permit the runs of the belt to pass up through it, one of these first receiving a device to take up slack in the belt. This device originates with a hanger 28 depending from the top of the stand, and supporting a pulley 29 over which the belt run last mentioned is trained. The latter then forms a bottom loop under a pulley 30, which carries a weight 31, and finally 15 ascends, as does the companion belt run, by way of two guide pulleys 32, which align the runs with the holes in the top of the stand. It will be obvious that the weight 31 will draw on the belt so as to eliminate 20 slack in the same without disturbing its motion.

The motor 22 is controlled by a standard snap switch 33 fitted in the top of the stand 14 so that the "on" and "off" push buttons for operating the same appear on the surface for handy reach by the clerk or salesperson. While the latter is expected to press the "on" button to start the motor, an automatic device is provided to stop the same. 30 The starting of the motor causes the belt to propel the carrier 11 along its course from the sending station to the point of destination. The belt, however, carries a tapered enlargement 34 which starts on the return trip as the carrier starts from the point of origin, so that the enlargement 34 may be assumed to approach the sending station by way of the descending belt run, at the time the carrier approaches the destination or receiving 40 station. To arrest the motion of the belt as the carrier enters its destination, the enlargement 34 is caused to depress a finger 35 positioned over the "off" button, with the result that the latter is pushed down and 45 the current cut off. The finger 35 is rockably disposed in a bearing 36 having a base plate 37 secured on the stand 14 between the "off" push button and the descending belt run; and that part of the finger 35 which 50 extends beyond the fulcrum carries a peripherally grooved roller 38, which, in the position denoted by full lines, borders on the path of the descending belt run. Opposite the roller 38 the path of the belt run 55 is lined by a hollow jaw 39, which is formed from the base plate 37. The belt run passes down between the roller and the jaw, and, as the enlargement descends between these, it crowds the roller out, causing the finger 60 35 to rock and depress the "off" button, whereby the current is cut off, and all motion of the mechanism ceases.

The track structure and the carrier associated with the same are of a design well known in the art, and therefore need not be

described in detail, other than to recur to the provision of the carrier with the arm 15, connecting the same with the ascending belt run. The latter passes through an aperture in the arm 15, first receiving a fixed collar 40, and a coil spring 41 between the collar and the arm. The latter is thus spring backed, and in striking an abutment 42 at the receiving station, will permit a gradual stop of the belt, reducing strain and vibration.

The abutment 42 forms part of a fixture 43, hung by a rod 44 of angular cross-section from a clamp 45, which is fastened by bolts 46 to a wall or railing bracket 47. 80 The rod 44 passes slidably through the jaws of the clamp, receiving a short coil spring 48 above same, and a long one 49 below. That part of the belt which continues upwardly from the arm 15 passes through an aperture in the abutment 42, and through apertures in the clamp jaws, then mounting the pulley 18 as sectionally shown in Fig. 4. Between the abutment 42 and the clamp, the belt passes freely through a coil spring 50. The upper end of the angular rod 44 is made to secure the spring 48 by means of a washer 50^a and cotter pin 50^b. It will now be seen that the impact of the carrier arm 15 with the abutment 42 is cushioned by the springs 49 and 50, with the rebound checked by spring 48.

In order that the carrier may remain elevated after its arm 15 has struck the abutment 42, said arm is caused to impinge upon a latch 51 pivotally hung at 52 from the fixture 43 and urged toward the arm's line of travel by a small spring 53. The latch is shown snapped over the arm 15 after the latter has stopped. The spring 53 is lodged between offsets 43^a and 51^a of the parts 43 and 51, the offset 51^a also serving as a handle which may be pressed up to swing the latch 51 back and release the carrier for descent.

In case it is not convenient to use the offset or handle to release the carrier, a device is provided whereby merely a tug of the belt will accomplish the result. A finger 54 is pivoted at 55 alongside the latch 51, with a continuation in the form of a dog 56. These two parts operate on the same pivot pin, and are caused normally to gather by the expansion of a spring 57 seated between two lugs 54^a and 56^a of the parts 54 and 56, respectively. The lug 54^a projects rearwardly from the finger 54, while the lug 56^a projects laterally from the dog 56. The assembly of the finger, and dog is normally in a position whereby the finger 54 crosses the path of the carrier arm 15, as shown dotted in Fig. 4. However, as the arm enters the latch 51, it pushes the finger back—as denoted by full lines in Fig. 4—so as to cause the dog 56 to advance upon the belt at a point above

the collar 40. The frontal side of the dog is vertically grooved to lie closer to the belt, and therefore assure its being directly in the path of the collar 40. While the finger 54 and dog 56 might be made in one piece and assume the positions described, the speed of the carrier and its cushioned stoppage demand the flexible break joint of the finger and dog to avoid clashing and breakage, the 10 spring 57 serving to cushion the contact of the dog with the belt or spring 41 encircling it. To operate the device the belt is given a tug in the direction of its previous travel. This action urges the dog 56 (through collar 40) upwardly, causing the pivot 55 to back and swing the latch 51 away from the carrier arm 15. The latter being free, the carrier drops of its weight, causing the belt to move in reverse direction.

20 If the carrier has an extended drop during the initial part of its return trip, it will accumulate sufficient momentum to continue its trip to the sending station without further manual or power assistance. Especially will this action be facilitated by the freedom of the belt from the motor 22, through the agency of the automatic clutch 25^a, 25^b, etc., so that the continuous return of the carrier will not suffer the resistance offered by the motor. It will be obvious that the tug mentioned may be imparted to the belt by the attendant at the sending station, in case the operator at the receiving station is thought to have overlooked the 30 return of the carrier to its home station.

In case a sufficient initial drop of the carrier cannot be arranged to enable the self return of the same, a power actuated return may be provided by the suitable adaptation 40 of the apparatus at the sending station to the structure at the receiving station. With this idea in mind, it will be obvious that the motor at the receiving station could be put into action by the pressing of a push button 45 governing a circuit independent from that of the motor at the sending station, so that a rapid return of the carrier to the latter may be effected.

An apparatus is thus provided which assures prompt and efficient carrier action with the use of few and simple parts, no electrical wiring other than ordinary service connections being employed.

I claim:

55 1. An overhead carrier system comprising a sending station, a receiving station, a wire track between the stations, an endless belt having its runs along the course of the track, power means for operating the belt, a carrier propelled by the belt along the track, a manually-operated starting control for the power means, and an automatic stopping control for the latter operative when

the carrier reaches the station of its destination.

65

2. An overhead carrier system comprising a sending station, a receiving station, a wire track between the stations, an endless belt having its runs along the course of the track, power means for operating the belt, 70 a carrier propelled by the belt along the track, a manually-operated starting control for the power means, an automatic stopping control for the latter operative when the carrier reaches the station of its destination, 75 and a device which automatically disconnects the belt from the power means when the latter is not in driving action.

3. An overhead carrier system comprising a sending station, a receiving station, a wire 80 track between the stations, an endless belt having its runs along the course of the track, power means for operating the belt, a carrier propelled by the belt along the track, a manually-operated starting control for the power means, an automatic stopping control for the latter operative when the carrier reaches the station of its destination, a latch 85 for the retention of the carrier after it has reached its destination, and belt controlled 90 means whereby said latch may be retracted to release the carrier.

4. An overhead carrier system comprising a sending station, a receiving station, a wire track between the stations, an endless belt 95 having its runs along the course of the track, an electric motor for operating the belt, a carrier propelled by the belt along the track, motor starting and stopping switch buttons located in proximity to the belt, an enlargement carried by the latter, a rockable finger adapted to depress the stopping button upon pressure exerted by said enlargement, and a back guide for the belt on the side opposite to that on which the finger is located.

100

5. A terminal for overhead carrier systems comprising a wire track for the carrier, a looped belt for the propulsion of the latter, a spring-backed bumper for an arm forming part of the carrier, a latch pivotally suspended from the bumper to engage the arm and form a retainer for the carrier, a spring between the bumper and the latch to urge the latter toward the arm, a finger pivotally mounted alongside the latch and adapted to 110 be backed by the entrance of the arm into the latch, a dog pivotally suspended from the latch and positioned alongside the incoming run of the belt, an abutment on such run adapted to strike the dog with the effect 115 of backing the latch out of engagement with the arm, and a spring directed from the finger to urge the dog toward the course of the said belt run.

105

In testimony whereof I affix my signature,

JAMES L. BALDWIN.
